S. J. BELL

FARE BOX

Filed Feb. 24, 1927

FIG. 1

FIG. 2

FIG. 3

FIG. 4

INVENTOR.

Samuel J. Bell,

BY

Frank A. Cutler,
ATTORNEY.

UNITED STATES PATENT OFFICE.

SAMUEL J. BELL, OF WEST SPRINGFIELD, MASSACHUSETTS, ASSIGNOR TO BELL REGISTER, INC., OF SPRINGFIELD, MASSACHUSETTS, A CORPORATION OF NEW YORK.

FARE BOX.

Application filed February 24, 1927. Serial No. 170,453.

My invention relates to improvements in devices for keeping an accurate account of the fares received by the conductors of passenger vehicles, and consists essentially of 5 a receptacle or casing having a slot in one end for the introduction of metal tokens or tickets, and equipped at the opposite end with a removable, lock-provided closure or plug, one or more separators or diaphragms 10 movably mounted in said casing, and adapted to be positioned to divide or separate the space in the casing into closed compartments, interior means to lock each of said diaphragms in closed position, exterior 15 means to move each of said diaphragms into closed and locked position, and a movable, interior member, capable of being moved only when said plug is removed from the casing, to prevent operation from the outside of said locking means for the purpose 20 of releasing therefrom said diaphragms, together with such other parts and members as may be necessary or desirable in order to render the device complete and serviceable 25 in every respect, all as hereinafter set forth.

The primary object of my invention is to produce a comparatively inexpensive and simple fare-box, especially adapted for use on interurban busses, although equally useful perhaps on other passenger-carrying vehicles, wherewith it is possible to obtain and have available an exact record of or check on the fares collected by the conductor. This fare-box can not be improperly 30 manipulated by the conductor, and its use makes it necessary for him to account to the company for the entire amount of money received by him as fares during the trip and which is due said company, and also prevents the passengers from defrauding the 35 company.

Another object is to produce a fare-box, of this character, which can be conveniently carried from office to vehicle and from vehicle to office, and requires very little space in the vehicle for its accommodation.

A further object is to furnish such a fare-box which requires no attention from the conductor except to close the diaphragms at 40 the proper times, and see that the passengers, when they enter and before they leave the vehicle, drop the tokens given them by the conductor into the fare-box.

This fare-box is set for use and locked 45 when given to the conductor. A key to the

fare-box is in the office where the fare-box is to be turned in. The set and locked fare-box can be manipulated while outside of the office only for the closing of the diaphragms. With the key in the office where 50 the fare-box is turned in said fare-box is unlocked and opened, the tokens are removed therefrom in proper sequence, and they accurately show the amount of the fares collected by the conductor who had the fare- 55 box.

Other objects and advantages will appear in the course of the following description.

I attain the objects and secure the advantages of my invention by the means illustrated in the accompanying drawings, in which—

Figure 1 is a side elevation and partial section of a fare-box which embodies a practical form of my invention; Fig. 2, a cross section through said fare-box, taken on lines 75 2—2, looking down, in Fig. 1; Fig. 3, a cross section through the fare-box, taken on lines 3—3, looking up, in Fig. 1; Fig. 4, a side elevation of the lower part of the fare-box, 80 with a fragment of the portion of the casing therein appearing broken out to disclose the outer side elevation of the lower-end portion of the lock bar, and, Fig. 5, a sectional detail of the lower part of the fare-box, illustrating the means employed for actuating 85 each latch to cause the same to release the associated diaphragm.

Similar reference characters designate similar parts throughout the several views.

In the first view the two lower diaphragms, and also the diaphragm immediately above which is hidden by the wall of the casing, are in closed position, while the two upper diaphragms, and also the two 95 diaphragms below which are hidden by said wall, are in open position, the plug is locked in place, and the lock bar is in closed position and prevented by said plug from being moved into open position. The fare-box, as 100 illustrated in this view, is ready for use, or, in fact, is in the act of being used; while said fare-box, as illustrated in Figs. 4 and 5, has had the plug, with the tokens thereon in the bottom compartment, removed from the 105 casing, and the lock bar moved into open position, and is ready to have the tokens dumped out of the several compartments, above said bottom compartment, by tripping each latch to release its diaphragm, begin- 110

ning with the bottom latch, which latter in Fig. 5 has already been tripped, and the tokens in the compartment immediately above said bottom compartment have 5 dropped out of the same and out through the now open bottom of said casing.

- Although I have shown the fare-box in cylindrical form, it is obvious that the same may be made square or of some other shape 10 in cross section, without altering any essential feature of the invention. I have also shown an eight-compartment fare-box, but a fare-box may be made to include more or less than that number of compartments, and 15 lengthened or shortened accordingly, variations in these respects being necessary in order to meet different conditions. There should be a compartment for each station where fare is paid.
- 20 The fare-box, as illustrated in connection herewith, comprises a casing 1 having at the top a fixed cap 4, a closure or plug 5 for the bottom of said casing, a plurality of separators or diaphragms 6 mounted to tilt or rock 25 on rods or shafts 7, a corresponding number of latches 8 for said diaphragms, said latches being pivotally mounted in the manner hereinafter explained, a spring 9 for each diaphragm and its latch, a vertical, sliding lock 30 bar 10, a vertical, fixed stop bar 11, and knobs or handles 12 on said shafts outside of said casing.

The casing 1 has rigidly secured thereto, on the inside, at the top and adjacent to the 35 bottom thereof, rings 13—13. The rings 13 reenforce the wall of the casing 1, and the bottom ring serves as a stop for the plug 5 when said plug is in place in said casing, and as a bolt-engaging member for two bolts 14 40 of a lock 15 with which said plug is equipped. A vertical bracket 16 is located against and rigidly secured to the casing 1 on the inside, said bracket extending from the upper ring 13 to within a short distance of the lower 45 ring 13. The bracket 16 has a side that is contiguous with the wall of the casing 1, and two inwardly extending sides, and said first-named side is offset inwardly, as clearly shown in Figs. 2 and 3, to provide space and 50 serve as a guide for the lock bar 10, which latter is located in said space, but extends below the bottom of said bracket. The latches 8 are located between the inwardly-extending sides of the bracket 16, and pivotally 55 connected at 17 with said sides. In the wall of the casing 1 in front of the downwardly-extending part or tail of each latch 8 is an opening 18, and directly behind said opening in the part of the bracket 16 that is contiguous with said wall is an opening 19. The stop bar 11 is rigidly secured against 60 the wall of the casing 1 inside. The bracket 16 and the bar 11 are located on radii of the casing 1 which radii are at right-angles to 65 each other.

In the present example, the cap 4 fits over the top of and around the outside of the wall of the casing 6 and is rigidly and permanently secured thereto. Preferably the top of the cap 4 is concave, and in the center of this concave part is a slot 20 of sufficient length and width for the passage through said slot of the metal tokens, one at a time, employed as counters, or more correctly as station and fare-amount indicators, 70 in and in connection with this fare-box. Certain of these tokens are represented in the first view and indicated by the numeral 21.

The plug 5 fits into the bottom of the casing 1 with the under side of said plug flush with the bottom edge of said casing, and when said plug is thus disposed the bolts 14, by means of a proper key for the lock 15, can be actuated into engagement with the upper edge of the lower ring 13, and out of such engagement. The periphery of the plug 5 has an annular shoulder 22 to receive the bottom edge of the lower ring 13. The plug 5, when locked in place, is securely held against movement in either direction on its axis, by the lower ring 13 and the bolts 14. Upon operating the lock 15 to retract the bolts 14, the plug 5 can be drawn out of the bottom of the casing.

In the lock bar 10 are openings 23, there being as many of these openings as there are openings 18 in the casing 1 and 19 in the bracket 16, and said first-named openings are so arranged in said bar that, when the bar is in raised position, the openings therein 95 are out of alignment with said casing and bracket openings, and, when the bar is in low position, its openings are in alignment with the other openings. The lower-terminal portion of the bar 10 is offset inwardly to enable such portion to clear the lower ring 13, and also to form a stop shoulder 24 to contact with the top of said ring, when said bar is moved downwardly, such movement being thus limited, and at the bottom of said 100 bar is an inwardly-extending finger 25 by means of which the bar is drawn downwardly. The upper ring 13 limits the upward movement of the bar 10. The bracket 16 must stop a sufficient distance above the 105 lower ring 13 to accommodate the offset part at the lower terminal of the bar 10.

When the plug 5 is removed, and the finger 25 is grasped and the bar 10 drawn downwardly until the stop shoulder 24 comes to rest on the ring 13 below, each hole 23 in said bar is in alignment with two of the aligning holes 18 and 19. The bar 10 is moved upwardly, either by hand, or by the plug 5 when inserted in the casing, to interpose solid portions of said bar between the aligning openings 18 and 19. The finger 25 then rests either on the upper surface of the plug or on the upper surface of one of the bolts 14, depending on the position of 110 115 120 125 130

the latter relative to said finger, consequently it is impossible to force the bar downwardly by inserting an instrument through any of the openings 18. Access otherwise to the 5 lock bar can not be had so long as the plug is locked in the casing.

Each diaphragm 6 has a central depression 26 which is mounted on and rigidly secured to one of the rock shafts 7, each of 10 which shafts has one terminal journaled in the stop bar 11, and the other terminal journaled in the wall of the casing 1 through which said last-named terminal extends to have mounted on and secured thereto one of 15 the handles 12. There is a recess 27 in each diaphragm 6 to accommodate the bar 11. The space between the parallel edges of the recess 27, in each diaphragm, is wide enough to receive the bar 11 and enable the dia- 20 phragm to be tilted at a fairly acute angle, or substantially as shown in the upper part of Fig. 1, before said edges contact with said bar. Each spring 9 has one end attached to one of the latches 8 above its pivot 25 17, and the other end attached to the associated diaphragm at a point beyond the shaft carrying said diaphragm, consequently said spring tends constantly to rock the latch so that the tail thereof is in contact 30 with the curved side of the bracket 16, and to tilt the diaphragm as far as the afore- 35 said edges of the recess 27 therein, by reason of their contact with the bar 11, permit. That portion of each diaphragm 6 which is 40 adjacent to the bracket 16 is cut away or recessed, as represented at 28, to enable said diaphragm when in horizontal position to clear said bracket, and to engage or be engaged by the associated latch 8, as shown in the lower part of Fig. 1.

The handles 12 are parallel with the diaphragms 6, hence the positions of the diaphragms can be determined from the outside by the positions of the handles. Upon 45 grasping any handle 12 which is disposed obliquely and turning it into a horizontal position, and, it will be remembered, the handle can be turned in one direction only because of the presence of the limiting stop bar 11, the shaft on which said handle is mounted is rocked and the diaphragm 6 on said shaft is moved into a horizontal position and engagement with the contiguous latch 8, against the resiliency of the spring 9 extending between said diaphragm and 50 said latch, the inner edge of the recess 28 in the diaphragm snapping into engagement with the notched part of the latch. The spring 9 connected with the diaphragm and latch just mentioned now retains said latch in engagement with said diaphragm, and causes the former to bear hard on the latch hook. The diaphragm thus disposed and 55 locked in horizontal position divides the space above from the space below the same,

and said diaphragm can not be released to assume its tilted position without rocking the associated latch 8 out of engagement therewith. This can be done only after the 60 plug 5 is unlocked and removed from the casing, and the lock-bar 10 drawn down with the stop shoulder 24 on the lower ring 13, and is accomplished by inserting an im- 65 plement, such as that represented at 29 in Fig. 5, into and through the aligning open- 70 ings 18, 23, and 19 in front of the tail of the latch to be disengaged from its associated diaphragm. The implement 29 has a terminal part sufficiently small to pass 75 through the openings provided to receive it. Upon forcing the small end of the im- 80 plement 29 through the openings against the tail of the latch, said latch is rocked on its pivot, against the resiliency of the connected 85 spring 9, until the upper part of said latch releases the associated diaphragm, when 90 said diaphragm is immediately caused to assume its tilted position, by the action of said spring. Then the implement 29 is with- 95 drawn, and the latch is rocked by the connected spring until the tail of said latch again bears against the curved side of the bracket 16, in which position the latch is left ready the next time to engage and lock 100 in horizontal position the associated dia- 105 phragm, upon the movement of said dia- phragm into closed position, by means of the associated handle 12.

There being in the present example seven 110 diaphragms 6, the casing 1 is thereby divided into eight compartments, when said dia- 115 phragms are horizontally disposed, the plug 5 forming the bottom of the lowest compart- 120 ment, and the cap 4 the top of the highest compartment, with the intermediate com- 125 partments located entirely between said dia- phragms.

Without attempting to explain in com- 130 plete detail the various ways in which the metal tokens, as 21, are or may be utilized in connection with my fare-box, I will, with the aid of the following examples, endeavor 135 to make clear what may be termed the method of using said fare-box, which method depends on the use of tokens, or equivalent objects, and is in a sense apart from the mechanical functioning of the fare-box, or perhaps it might more accurately be said that it supplements such function- 140 ing. It is to be understood that the tokens bear numbers indicative of the stations on the route over which the passenger vehicle carrying the fare-box travels, and that there are multiples of two tokens bearing 145 the same numeral for each station.

The fare-box is handed to the conductor with all of the diaphragms 6 in tilted position, and the plug 5 locked in the casing. The conductor is also supplied with the re- 150 quired quantity of tokens bearing numerals

from I to VIII, Roman numerals being here used to avoid confusion in the description.

Before the vehicle starts initially, each passenger as he boards the same receives 5 from the conductor two tokens 21 bearing the numeral of the station at which the passenger is to disembark, and the passenger drops one of his tokens into the slot 20 in the cap 4. The token 21 drops onto and 10 slides down the uppermost diaphragm 6, and continues in its downward course until it reaches the plug 5. Assuming that the conductor gives one passenger two tokens each bearing the numeral II, and each of 15 two passengers two tokens each bearing the numeral III, there are deposited in the lowest compartment three tokens, one of which bears the numeral II, and each of the other two bears the numeral III. As soon 20 as the conductor leaves the zone of the first station he turns the bottom handle 12 to close with the bottom diaphragm 6 the entrance from above to the bottom compartment, and prevent the tokens in said compartment from being removed therefrom.

Assuming that the fare between each of the stations is 25¢, the conductor has received from one of the three passengers 25¢, and from each of the other two passengers 30 50¢, or \$1.25 in all.

During the remainder of the trip the conductor hands to each passenger as he boards the vehicle two tokens each bearing the numeral of the station at which the passenger 35 is to disembark, and in each case one of these tokens is dropped into the fare-box and passes down onto the diaphragm last closed. Upon leaving each subsequent station the conductor closes the diaphragm 6 for that 40 station, by means of the handle 12 associated with said diaphragm, and thus locks into the space between said diaphragm and the closed diaphragm below the tokens in said space. At the end of the line the top 45 diaphragm 6 is closed. Meanwhile, as each passenger leaves the vehicle he deposits his second token in the fare-box and it lands on the diaphragm last previously closed. Thus the second number II token is deposited in 50 the compartment between the two lower diaphragms, each of the two number III tokens is deposited in the third compartment above the plug 5, and so on.

The fare-box with all of the diaphragms 55 closed and locked is now taken to the office, and there the plug 5 is unlocked and removed, the bar 10 is drawn down, and, beginning at the bottom, one latch 8 after the other is tripped, with the aid of the implement 29, the casing 1 being moved each time to deposit the tokens from the several compartments in separate piles or different places, respectively. Then the casing 1 is closed with the plug 5, and the bar 10 moved 60 65 upwardly to prevent access from the outside

to the latches 8, when the fare-box, after locking said plug in place, is again ready for the conductor.

In the first pile of tokens, which consists of the tokens from the bottom compartment taken out when the plug was removed, are three tokens one of which is number II and each of two of which is number III, and so on. Considering only the six tokens illustrated in the drawing, it will be seen that 75 the number II token from the second compartment corresponds with the number II token from the first compartment, and calls for the payment to the company by the conductor of 25¢, and that the two number III tokens from the third compartment correspond with the two number III tokens from the first compartment, and call for the payment of \$1.00, making the total of \$1.25.

A passenger getting on at the third station and paying 75¢ to ride to the sixth station, receives two number VI tokens, one of which he drops in at once and it is received in the third compartment from the bottom, and the other of which he drops in, when he gets off, and it goes into the sixth compartment from the bottom. The conductor must, therefore, pay to the company 75¢ to balance these two number VI tokens from the third and sixth compartments.

Usually the terminal stations are located in cities where stops are made, and in this case two number I tokens are given to an interurban passenger when he enters the vehicle at the first terminal station and pays his fare, which may be assumed to be 10¢. The passenger at once inserts one of the number I tokens in the fare-box, and inserts the other in said fare-box when he leaves the vehicle, so that both are found among those taken from the first compartment, and call for 10¢ from the conductor. The same applies to the top compartment in connection with the last station, except that in this case the two tokens are numbered VIII.

In the event a passenger desires to leave the vehicle before he arrives at the station to which he has paid his fare, and receives back from the conductor the difference between the fare to the station to which the passenger has paid and that to the station where he is to leave, the fact is made known in the manner outlined below.

Let it be assumed that the passenger pays a through fare, of \$2.00, deposits one of the number VIII tokens in the fare-box, which token finds its way into the bottom compartment, and subsequently decides to leave the vehicle at next to the last station. Upon so informing the conductor the passenger receives back 25¢, and when he leaves the vehicle deposits the second number VIII token in the fare-box and the same enters the seventh compartment from the bottom. Then, when the tokens are matched up in 125 130

the office, it is found that the number VIII tokens in one pair come from the bottom and sixth compartments, and only \$1.75 is required from the conductor to balance these 5 two tokens.

Numerous other examples might be given, but it is believed the foregoing are all that are necessary to understand clearly the manner in which the fare-box serves as a means 10 for accurately checking up and verifying the amount of money for fares received by the conductor on each trip.

More or less change in the shape, size, construction, and arrangement of some or all 15 of the parts of this fare-box, in addition to those hereinbefore specifically pointed out, may be made, without departing from the spirit of my invention or exceeding the scope of what is claimed.

20 What I claim as my invention, and desire to secure by Letters Patent, is—

1. In a fare-box, of the class described, a receptacle for tokens, movable members in said receptacle adapted to divide the same 25 into two or more closed compartments, locking means for said members in said receptacle, said members being provided with means outside of said receptacle for actuating said members into engagement with said locking means, and movable means accessible 30 for actuation only from inside of said receptacle, capable, according to disposition, of exposing said locking means for tripping purpose, and of preventing said locking 35 means from being tripped.

2. In a fare-box, of the class described, a receptacle provided with a removable end closure, and with one or more movable diaphragms dividing said receptacle into compartments which may be closed thereby, means to lock said diaphragms in closed position, said locking means being adapted to be tripped with a suitable implement introduced from outside of the receptacle, interior movable means to open and close the 40 way for such implement, and exterior means to move said diaphragms into engagement with said locking means.

3. In a fare-box, of the class described, a receptacle provided with a removable end closure, and with one or more movable diaphragms dividing said receptacle into compartments which may be closed thereby, means to lock each of said diaphragms in closed position, said locking means being adapted to be tripped with a suitable implement introduced from outside of the receptacle, interior movable means to open and close the way for such implement, said last-named means being accessible for operation 45 only when said closure is removed, and exterior means to actuate each of said diaphragms into engagement with its locking means.

4. In a fare-box, of the class described, a

receptacle provided with a removable end closure, one or more diaphragms movably mounted in said receptacle, and adapted when in open positions to afford access to the space below, and when in closed positions 70 to prevent access to said space, means to retain said diaphragms normally in open position, means to lock said diaphragms in closed positions, exterior means to move said diaphragms into engagement with said locking means, and means to prevent said locking means from being tripped while said closure is in place.

5. In a fare-box, of the class described, a receptacle provided with a removable end 80 closure, one or more diaphragms movably mounted in said receptacle, and adapted when in open positions to afford access to the space below, and when in closed positions to prevent access to said space, means 85 to lock said diaphragms in closed position, exterior means to move said diaphragms into engagement with said locking means, and movable means, capable of being moved only upon the removal of said closure, to afford access to said locking means for the purpose of disengaging the same from said diaphragms.

6. In a fare-box, of the class described, a perforated receptacle provided with a removable end closure, one or more diaphragms movably mounted in said receptacle, and adapted when in open positions to afford access to the space below, and when in closed positions to prevent access to said 95 space, means to retain said diaphragms normally in open position, latches mounted in said receptacle behind the perforations therein, and adapted to lock said diaphragms in closed positions, exterior means 100 to move said diaphragms into engagement with said latches, and means to close and keep closed said perforations while said closure is in place, and to open said perforations, upon the removal of said closure, to afford access to said latches for the purpose 105 of tripping the same.

7. In a fare-box, of the class described, a casing provided with a removable end closure, one or more shafts, diaphragms, and 110 a corresponding number of latches mounted in said casing, said latches being for said diaphragms, and means held in place by said closure to prevent said latches from being tripped, but capable of being moved, when 115 said closure is removed, to enable said latches to be tripped.

8. In a fare-box, of the class described, a casing provided with a removable end closure, one or more shafts journaled in said 120 casing, and provided outside of said casing with handles, a corresponding number of diaphragms secured to said shafts, a corresponding number of latches, for said diaphragms, mounted in said casing, a spring 125

connecting each diaphragm with its latch, and adapted normally to retain the diaphragm in tilted position and the latch in engaging position, and means to enable said 5 latches to be tripped from outside of said casing when said closure is removed.

9. In a fare-box, of the class described, a casing provided with a removable end closure, one or more diaphragms mounted 10 in and capable of being operated from the outside of said casing, latches, for said diaphragms, mounted in said casing, said casing having perforations therein, adjacent to said latches, to enable the latter to be tripped 15 by means of an implement introduced from outside, and movable means in said casing adapted to prevent said latches from being tripped by said implement when said closure is in place, and capable of being moved, when 20 said closure is removed, to enable said latches to be operated by said implement.

10. In a fare-box, of the class described, a casing provided with a removable end closure, one or more shafts journaled in 25 said casing, and provided outside of said casing with handles, a corresponding number of recessed spring-pressed diaphragms secured to said shafts, a stop bar in said casing and passing through the recesses in said dia- 30 phragms to limit the movement imparted to the diaphragms by their springs, spring-pressed latches, for said diaphragms, mounted in said casing, and means to enable said latches to be tripped from outside of the 35 casing when said closure is removed.

11. In a fare-box, of the class described, a casing provided with a removable end closure, one or more shafts journaled in and provided with handles outside of said casing, a corresponding number of spring-pressed diaphragms secured to said shafts, means to limit the movement imparted to 40 said diaphragms by their springs, spring-pressed latches mounted in said casing in op- 45 erative positions relative to said diaphragms, said casing having perforations therein, adjacent to said latches, to enable the latter to be tripped by means of an implement introduced from the outside, and a lock bar slid- 50 ingly arranged in said casing between said perforations and said latches, and having therein perforations adapted to be brought 55 into registry with said first-named perforations, said bar being retained with its perforations out of registry with the casing perforations by said closure when in place.

12. In a fare-box, of the class described, a perforated casing provided with a removable end closure, one or more shafts journaled in and having handles thereon outside of said casing, a corresponding number of spring-pressed diaphragms secured to said shafts, means to limit the movement imparted 60 to said diaphragms by their springs, a

perforated bracket secured in said casing, 65 spring-pressed latches pivotally connected with said bracket in positions to engage said diaphragms when moved into closed positions, and a perforated lock bar slidingly arranged between said bracket and said casing, 70 and retained in closed or locking position when the closure is in place, the perforations in said casing and bracket being in positions to afford access from the outside for a tripping implement to said latches, and the perforations in said bar being adapted to register with the other perforations when said bar is moved in one direction, and said bar being adapted to close said other perforations 75 when moved in the opposite direction. 80

13. In a fare-box, of the class described, a perforated casing having near the bottom a projection, and provided with a removable end closure, one or more shafts journaled in and having handles thereon outside of said casing, a corresponding number of spring-pressed diaphragms secured to said shafts, 90 means to limit the movement imparted to said diaphragms by their springs, a perforated bracket secured to said casing, spring-pressed latches pivotally connected with said bracket in positions to engage said diaphragms when moved into closed positions, the perforations in said casing and bracket being in positions to afford access 95 from the outside for a tripping implement to said latches, and a perforated lock bar slidingly arranged between said casing and bracket, and retained in closed or locking position when said closure is in place, the perforations in said bar being adapted to register with the other perforations when said bar is moved in one direction, and said bar being adapted to close said other perforations when moved in the opposite direction. 100

14. In a fare-box, of the class described, a casing having at the top a fixed cap with a slot therein, and at the bottom a bolt-engaging member, a plug receivable in the lower end of said casing, and provided with a lock having a bolt to engage said member, one or more spring-pressed diaphragms in said casing, outside operating means for said diaphragms, spring-pressed latches for said diaphragms, said casing having perforations therein to permit a tripping implement, for said latches, to be introduced from the outside, and a sliding lock bar in said casing between the wall of the same and said latches, said bar being retained in closed position relative to said perforations when said plug is in place, and having perforations therein to register with said first-named perforations when said plug is removed and said bar drawn downwardly. 110 115 120 125

SAMUEL J. BELL.
